SET OF TOY CARDS OR SIMILAR ARTICLE

Gilbert Deschatre, Rio de Janeiro, Brazil

Application December 3, 1953, Serial No. 27,875

Claims priority, application Brazil August 21, 1953

Term of patent 14 years

(Cl. D34—13)

FIG. 1

FIG. 2

FIG. 3

FIG. 4

FIG. 5

FIG. 6

FIG. 7

Fig. 1 is a face view of seven of the cards in a set of toy cards or similar article, showing my new design;

Fig. 2 is a face view of another twelve cards in the set;

Fig. 3 is a face view of another nine cards in the set;

Fig. 4 is a face view of another seven cards in the set;

Fig. 5 is a face view of another twelve cards in the set;

Fig. 6 is a face view of another nine cards in the set; and

Fig. 7 is a face view of the remaining ten cards in the set.

The cards are of no appreciable thickness and the backs thereof are conventional.

I claim:

The ornamental design for a set of toy cards or similar article, as shown and described.
